UNITED STATES PATENT OFFICE.

THORSTEIN SKORNING, OF CHICAGO, ILLINOIS.

SCOURING OR CLEANING DEVICE.

1,175,481.

Specification of Letters Patent. Patented Mar. 14, 1916.

Application filed November 13, 1915. Serial No. 61,296.

To all whom it may concern:

Be it known that I, THORSTEIN SKORNING, a subject of the King of Norway, residing at Chicago, in the county of Cook 5 and State of Illinois, have invented certain new and useful Improvements in Scouring or Cleaning Devices, of which the following is a specification.

This invention relates more particularly 10 to a device which is intended for scouring or polishing knives, forks, and the like. Its objects are to provide a device of this character which is simple in construction and may therefore be made at a small cost, and 15 one which will be durable and efficient in operation.

In the accompanying drawings illustrating this invention: Figure 1 is a side view, showing the device applied to a table; Fig. 20 2 is a longitudinal sectional view; and Fig. 3 is a front elevation.

As shown in these drawings, 5 represents a casing, comprising side members 6 and a bottom 7. A stop or cross-piece 8 is secured 25 to the bottom at the front end of the device, for engagement with the edge of a table top or shelf, upon which the device rests when in use, so that the operator may hold the same firmly in position. A tongue 30 or partition-like member 9 is pivoted at 10 at the back of the casing, the pivot 11 passing through the side walls 6. The front of the tongue or plate 9 is provided with projections 12, which serve as thumb pieces or 35 handles, for raising and lowering the front end thereof. The lower surface of the tongue or plate 9 is substantially flat or plain, and normally lies about parallel with the upper surface of the bottom 7. It is 40 provided with a covering 13, of felt or the like, and the upper surface of the bottom 7 is provided with a similar covering 14. The upper surface of the tongue or plate 9 is curved as indicated, such curvature 45 corresponding to the general curvature of forks or other curved articles which are to be cleaned or polished in the device. A second tongue or plate 15 is pivoted at the back of the casing, as indicated at 16, the pivot 50 17 extending through the side walls and engaging with the plate. The lower surface of this tongue or plate is curved to conform with the upper surface of the tongue or plate 9, and the front end thereof is provided with projections 18, which serve as 55 handles for raising and lowering the same,

The lower surface of the tongue or plate 15 is provided with a covering 19 of felt or the like, and the upper surface of the plate 9 is provided with a similar covering 60 20. The pivots 11 and 17 may be more or less permanent, or they may be formed so as to be readily removed to release the plates for renewing the felt or for cleaning.

When the device is to be used, some abrading or polishing material is placed on the cloth or felt coverings, and if a knife is to be cleaned, the operator raises the outer end of the tongue or plate 9, and inserts the knife between the coverings 13 and 14, and 70 the knife is polished by moving the blade back and forth between these coverings, the operator in the meantime regulating the pressure and holding the device in position on a table, by pressing down on the plate 15. 75

If a fork is to be cleaned, it is inserted between the coverings 19 and 20 of the two plates, and the operation is the same as above described. The coverings between the different parts may be made of polishing cloth or any other suitable material, either for polishing or for holding abrading or polishing material, which may be applied thereto; and the form of the device may also be altered without departing 80 from the general nature of my invention. Therefore I do not wish to limit myself to the exact construction shown and described, except as pointed out in the following claims, in which— 85 90

I claim:

1. In a device of the character set forth, the combination of a casing, a plate pivoted at the back of the casing, having a flat lower surface and a longitudinally curved 95 upper surface, a second plate having a longitudinally curved lower surface pivoted at the back of the casing, and coverings of fabric between the opposed surfaces of the plates, and between the lower surface of the first-named plate and the upper surface of the bottom of the casing.

2. In a device of the character set forth, the combination of a frame comprising a bottom and side members, a downwardly 105 projecting cross-piece on the bottom at the front thereof, a tongue extending longitudinally of the frame, and pivoted at the back thereof, a handle at the front end of said tongue, said tongue having a flat lower surface which is normally substantially 110 parallel with the bottom plate, and having

a longitudinally curved upper surface, said curvature corresponding in general with the curvature of an article to be cleaned, a second tongue extending longitudinally of the frame, and pivoted at the back thereof, said tongue having a handle at the front, and having its lower surface curved lon-

gitudinally to conform to the upper surface of the first-named tongue, and coverings for holding cleaning material, placed on the opposed surfaces of the tongues and on the lower surface of the first-named tongue and upper surface of the bottom plate. 10

THORSTEIN SKORNING.
